Primary Examiner — Keli L Hill*Assistant Examiner* — Harold E Blackwell, II(74) *Attorney, Agent, or Firm* — Lorenz & Kopf, LLP(57) **CLAIM**

The ornamental design for a corner key for fenestration unit frame, as shown and described.

DESCRIPTION

FIG. 1 is a front isometric view of a corner key for fenestration unit frame showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines in the drawings illustrate portions of the corner key for fenestration unit frame which form no part of the claimed design.

1 Claim, 7 Drawing Sheets(56)
